UNITED STATES PATENT OFFICE.

FERD L. CRAMPTON, OF KANSAS CITY, MISSOURI.

AUTOMATIC CLOSING ATTACHMENT FOR VALVES.

Application filed December 12, 1921. Serial No. 521,694.

To all whom it may concern:

Be it known that I, FERD L. CRAMPTON, a citizen of the United States, and resident of Kansas City, Jackson County, State of Missouri, have invented a certain new and useful Improvement in Automatic Closing Attachments for Valves, of which the following is a complete specification.

This invention relates to automatic closing attachments for valves, and more especially for valves controlling the supply of liquid fuel to burners for furnaces and the like, my primary object being the production of simple and efficient means for catching fluid overflowing from the burner in the event of the accidental extinguishment of the flame, and utilizing the weight of such fluid for closing the valve to cut off the further supply of fluid to the burner.

20 A further object is to provide means for applying auxiliary force, in the shape of a blow or impact, to insure the full and complete closure of the valve after the weight of the fluid has started the valve on its closing movement.

With these objects in view, the invention consists in certain novel and useful features of construction and combinations of parts as hereinafter described and claimed; and in order that it may be fully understood, reference is to be had to the accompanying drawing, in which:

Figure 1 is a side elevation of a burner equipped with an attachment embodying the invention.

Figure 2 is an end view of the same.

Figure 3 is an enlarged vertical section taken on the line III—III of Figure 2.

Figure 4 is a section taken on the line IV—IV of Figure 3.

Figure 5 is a section on the line V—V of Figure 3.

In the said drawing, 1 indicates a fuel supply pipe leading to a burner 2 of any suitable type, the fuel being supplied under gravity pressure or any other pressure, and said pipe is provided with the customary valve 3 for regulating the degree of operation of the burner. It is also provided with a valve 4, the stem of which is formed with a rectangular or squared outer portion 5 and a shoulder 6 at the inner end of said portion.

55 A rocking beam 7 is provided with a circular opening 8 fitting upon and rotatably adjustable on the rectangular or squared portion 5 of the stem, and said beam is pro-

vided at opposite sides with roughened or rosette faces 9 around the said opening 8.

A rosette collar 10 is non-rotatably mounted on the stem at the inner side of said beam, 60 and a rosette collar 11 is journaled or rotatably mounted on the stem at the outer side of said beam, the said rosette collars engaging the rosette faces or portions of the beam, and in order that said parts shall be clamped 65 firmly together and thus be incapable of movement independent of like movement by the valve, a washer 13 is fitted against the outer end of the valve stem and against the outer face of collar 11 to close the opening 70 12 thereof, and a screw bolt 14 extends through said washer and into said stem, the screwing home of said bolt clamping the said collars and the said beam firmly together. 75

A receptacle 15 is suspended by a link 16 or in any other suitable manner from one end of said beam and tends to rock the same in the proper direction for effecting closing action of the valve, the parts being so proportioned however as shown most clearly by Figure 2, that the valve normally stands open.

The rocking beam has up turned ends through which extend a rod 17, the end of 85 said rod at what may be termed the heavy end of the beam, being provided with threads and carrying an adjustable poise or weight 18, the adjustment of which determines the delicacy of operation of the valve. 90 The said rod between the up turned ends of the beam is smooth, and mounted slidingly thereon is a weight 19.

When the valve is open the rod 17 is pitched downwardly at a suitable angle toward the heavy end of the beam so that the weight 19 shall slide to such end of the beam and hence cooperate in holding the valve open. 95

A part of the attachment comprises a pan 100 arranged below the burner so that oil overflowing from the latter shall fall in said pan, and said pan is equipped with a drain tube 21 for discharging the oil caught by the pan into the receptacle 15. The pan and tube may be supported in any suitable manner and occupies a fixed relation with respect to the burner. 105

With the parts arranged as shown and described and assuming that the flame at 110 the burner becomes extinguished from any cause, it will be apparent that the oil will

overflow from the burner and fall into the pan and pass from the latter through said tube into the receptacle 15 and eventually raise the weight of the latter to more than 5 counterbalance the heavy or weighted end of the beam. As a result, the receptacle-carrying end of the beam will swing downward and begin closing movement of the valve. In this rocking action of the beam, 10 its heavy end will rise to a higher plane than the receptacle carrying end and as a result, the weight 19 will slide upon the rod 17 and after it passes a certain point will cooperate with the receptacle in the valve 15 closing movement, the impact of the sliding weight against the receptacle-carrying end of the beam tending to insure a complete and full closure of the valve, the parts being so proportioned that when the valve is 20 fully closed, the weights 18 and 19 occupy such positions that they cooperate with the weighted receptacle in holding the valve in such position. To reset the attachment, the liquid fuel in the receptacle is drawn or 25 poured off and then the beam is rerocked to its initial position as shown by full lines in Figure 2, the weight 19 sliding to the left and thus cooperating with the weight 18 in holding the valve reliably open.

30 From the above description it will be apparent that I have produced an attachment embodying the features of advantage set forth as desirable in the statement of the objects of the invention, and which may be 35 obviously modified in minor particulars without departing from the principle of construction and mode of operation involved.

What I claim is:

1. The combination with a liquid fuel 40 burner and a valve for controlling the flow of fuel to the burner, of an automatic closing attachment for the valve, comprising a device movable rotatably as the valve is closed or opened, and normally holding the 45 valve in the last-named position, a receptacle exerting force tending to cause the device to rock and close the valve, an adjustable weight for cooperation in holding the valve normally in open position, a slidable

weight for cooperating with the first-named 50 weight in holding the valve open and for movement toward and impact against the said device at the receptacle carrying end thereof when the valve is closing, and means for discharging liquid into the receptacle 55 to cause the same to over-balance the said device and weight and start closing movement of the valve.

2. The combination with a rotatable valve, of a beam rotatably adjustable on the stem 60 of said valve, means for securing said beam in rigid relation to the valve, an adjustable weight movable with the beam and tending to hold the same with the valve in open position, a receptacle to be weighted for 65 rocking the beam and closing the valve, and a weight slidable longitudinally of the beam and adapted when the valve is closed to cooperate with the first-named weight in holding the valve open and to slide toward the opposite end of the beam after the valve is started on its closing movement by the weighting of the receptacle, to strike said beam, and cooperate with said receptacle in insuring the complete closure of the 75 valve.

3. The combination with a fuel supply pipe, of a valve controlling said pipe, a beam secured to the valve and provided with upturned ends, a rod secured to the 80 beam and extending from one of its arms through the other arm, a weight manually-adjustable on the rod, a weight slidable on the rod between the upturned ends of the beam and a receptacle suspended from the 85 beam at the opposite side of the valve from the adjustable weight, said receptacle when sufficiently weighted imparting movement to the beam for closing the valve and thereby causing the slidable weight to slide upon 90 said rod away from the adjustable weight and by striking the opposing upturned end of the beam, cooperate with the weighted receptacle in closing the valve.

In witness whereof I hereunto affix my 95 signature.

FERD L. CRAMPTON.
